UNITED STATES PATENT OFFICE.

HERBERT COTTRELL, OF NEWARK, NEW JERSEY.

AIR-CARBURETING APPARATUS.

SPECIFICATION forming part of Letters Patent No. 249,013, dated November 1, 1881.

Application filed April 22, 1881. (No model.)

To all whom it may concern:

Be it known that I, HERBERT COTTRELL, of Newark, in the county of Essex and State of New Jersey, have invented certain new and 5 useful Improvements in Air-Carbureting Apparatus, of which the following is a specification.

My invention relates to improvements in that well-known kind of air-carbureting apparatus in which the hydrocarbon vapor, before being 10 mixed with the air, is employed as a motive agent for working an air-pump to supply air to the mixing-chamber, and for working another pump for supplying hydrocarbon liquid to the vaporizing-chamber.

15 My invention consists in the combination of an air-pump cylinder, an engine-cylinder arranged in line therewith, an interposed mixing-chamber communicating with a gas-reservoir, passages from both of said cylinders to 20 said mixing-chamber for delivering hydrocarbon vapor and air into said chamber, pistons fitted to said cylinders, and a piston-rod connecting said pistons and working through said mixing-chamber, whereby I produce a compact 25 apparatus so constructed that any air or gas which may escape through the piston-rod stuffing-boxes is delivered into said mixing-chamber. The engine and pump cylinders are preferably secured at the ends to said mixing-chamber and supported thereby, and the said mixing-chamber also serves as a means for supporting 30 the gas reservoir or holder, whereby the construction of the apparatus is greatly simplified.

Another part of my invention is applicable 35 to apparatus in which hydrocarbon liquid is injected into the valve-chest of the engine and there vaporized by heat applied to the exterior of said valve-chest, and consists in the combination, with an air-pump, an engine, means for 40 heating the valve-chest of said engine externally, and a gas reservoir or holder comprising a movable top, of a pump for supplying hydrocarbon liquid to the engine-cylinder, mechanism connected with the engine for operating 45 the pump-plunger to cause the pump to fill with liquid, a spring or weight for effecting the opposite movement of the pump-plunger, a catch for holding said plunger against the force of the spring or weight, and a rod connected with the movable top of said reservoir or holder for releasing the pump-plunger to

55 permit its operation by the spring or weight, whereby the supply of hydrocarbon liquid and the operation of the engine are regulated by the supply of gas contained in the reservoir or holder. The engine is provided with suitable valve-operating mechanism, and the plunger of the pump for supplying hydrocarbon liquid is preferably "set" or moved to cause the liquid to fill the pump by mechanism connected 60 with the valve-operating mechanism, and after the plunger is so set it is held by the catch, while the valve-gear continues to operate without again moving the plunger until the latter is released from its retaining-catch by the decrease of gas in the reservoir or generator. 65

In the accompanying drawings, Figure 1 represents a longitudinal section through a carbureting apparatus embodying my invention; and Fig. 2 represents a side view of said apparatus, looking from the opposite direction to that indicated by said section. 70

Similar letters of reference designate corresponding parts in both the figures.

A designates the air-pump cylinder for supplying air to be carbureted, and B designates a piston fitted to reciprocate therein. 75

C designates the engine-cylinder, and D the piston thereof, by which the air-pump piston is operated. As here represented the cylinders are arranged in line, and the pistons B and D are secured to a common piston-rod, E. 80

F designates a mixing-chamber interposed between the cylinders A and C, and receiving from them hydrocarbon vapor and air, which are mixed therein to form gas. The gas reservoir or holder G, with which the mixing-chamber communicates, is in the present instance placed above and supported upon the mixing-chamber, which latter also forms a part of said reservoir or holder. The reservoir or holder is constructed with a movable top, G', having the usual water-seal, a, though the reservoir might be of bellows form. 85

The air-pump, which is represented as double-acting, is constructed with inlet or suction valves b at each end, and outlet or discharge valves c, through which air is discharged into a discharge-chest, A', and supplied to the mixing-chamber F through a duct or passage, d. 90 The engine is also represented as double-acting, and the exhaust hydrocarbon vapor is de- 95

livered therefrom through a duct or passage, *e*, to the said mixing-chamber.

It will be observed that the air-pump and engine cylinders are secured at the end to the 5 mixing-chamber *F*, thereby supporting the cylinders and effecting the connection of the air and exhaust vapor passages with the mixing-chamber without the necessity of pipe-connections, thereby simplifying the apparatus 10 and lessening the danger of leakage. It will also be observed that inasmuch as the piston-rod *E* works through the mixing-chamber, the stuffing-boxes *f* for said rod are packed from the inside of the mixing-chamber, and any vapor or air that may escape from the air-pump cylinder *A* and engine-cylinder *C* will be discharged into the mixing-chamber, and any loss 15 from leakage thereby obviated.

The mixing-chamber *F* is provided at its bottom 20 with a pipe, *g*, for drawing off any hydrocarbon liquid which may accumulate in the said chamber through condensation, and said chamber is also provided with a pipe, *h*, for the discharge of gas or carbureted air from 25 the reservoir or holder *G*.

The engine-cylinder *C* which I have here 30 represented is provided with a chest, *C'*, made separate from the cylinder and arranged upon the under side thereof. This chest is constructed with suitable induction and exduction 35 ports, and the valve, here represented as an ordinary slide-valve, *H*, works upon the upper inner face of the chest as a seat, and is moved by a toe, *i*, upon a rock-shaft passing through the side of the chest and having an attached 40 arm, *j*, outside the chest. (See Fig. 2.)

The piston-rod *E* within the mixing-chamber *F* is provided with a disk, *I*, of oblate-spheroidal or lens-like form, and *J J* designate 45 curved arms supported on a rock-shaft, *K*, inserted through the side of the mixing-chamber. The arms *J J* embrace or project upon each side of the disk *I*, and by the longitudinal movement of the piston-rod *E* the disk is caused to 50 act upon said arms and impart an oscillating motion to the rock-shaft *K*. Upon the outside of the mixing-chamber is a bar, *L*, supported so as to permit of its longitudinal movement, and having two projecting tappets or projections, *k k*.

M designates a weighted trip-lever loosely pivoted upon the rock-shaft *K*, and provided with a toe, *l*, projecting between the tappets *k*.

N designates a collar or hub fixed upon the 55 rock-shaft *K*, and having a peripheral recess, *m*, receiving a pin, *n*, projecting from the trip-lever *M*. The bar *L* is connected by a link, *o*, with the arm *j*, and by its longitudinal movement imparts the desired movement to the 60 valve *H*.

It is obvious that as the rock-shaft *K* commences its oscillation the end of the peripheral recess *m* in the hub or collar *N*, bearing upon the pin *n* in the lever, moves said lever upward 65 toward a vertical position; but as soon as said lever passes said vertical position its weight

causes it to fall and complete the throw of the bar *L* and the movement of the valve *H*.

In the engine here represented hydrocarbon liquid is supplied to the valve-chest *C'* through 70 a pipe, *p*, and vaporized by means of gas-burners *q*, arranged underneath the chest, or any other suitable means.

O designates a pump for supplying hydrocarbon liquid to the valve-chest *C'* from any 75 source of supply. As here represented, the plunger of the pump *O* is operated by a lever, *P*, pivoted at *r*, and the end of which lever is adapted to engage with a stop or detent, *s*, here shown as consisting of a curved plate provided with a hole for receiving the end of the 80 said lever.

Q designates a rod or link having a slotted connection with the toe *l* and lever *P*, and serving to depress the lever *P* when the latter is 85 elevated, and cause it to engage with the stop or detent *s*; but, owing to the slotted connection of the link *Q* with the toe *l* and lever *P*, the engine may continue working when the lever *P* is depressed or set without imparting 90 any further motion to it.

R designates a spring which is compressed by the operation of setting the lever *P*, and which, as soon as the said lever is released from the stop or detent *s*, will impart an upward movement to the lever and force the liquid contained in the pump *O* into the valve-chest *C'*. 95

S designates a rod held in a suitable guide, *t*, and adapted to be depressed by a lug or ear, *u*, (see Fig. 1,) upon the movable top *G'* of the reservoir *G* striking its upper end. When the said rod is forced down its lower end strikes the curved stop or detent *s*, and, forcing it to one side, releases the lever *P* and permits the spring *R* to actuate the pump-plunger to throw a charge 100 of hydrocarbon liquid into the valve-chest *C'*. By the next movement of the engine the lever *P* and spring *R* will be set by the link *Q*, and the plunger of the pump *O*, which may be of 105 a size or have its stroke adjusted to hold liquid for effecting one or more strokes of the engine-piston, will be raised to cause the pump to fill with liquid. The engine will then work until the supply of liquid injected into the chest *C'* 110 is all vaporized and exhausted without imparting any further movement to the lever *P*, which is all vaporized and exhausted without imparting any further movement to the lever *P*, which will be held by the detent *s* until the supply of gas in the reservoir or holder *G* becomes so much reduced that the rod *S* is depressed by 115 the downward movement of the movable top *G'* and caused to release the lever *P* from the stop or detent *s*. The spring *R* will then throw said lever upward, injecting a new supply of liquid into the valve-chest *C'*, and causing the engine 120 to resume its operation.

It is obvious that a weight might be suitably arranged to take the place of the spring *R*.

It will be understood that the operation of the engine and the discharge of air into the 130 mixing-chamber are automatically controlled by regulating the injection of hydrocarbon liq-

uid into the valve-chest C', and that the hydro-carbon liquid may be stored at any desired distance from the building containing the apparatus and supplied to the engine by the pump 5 in just such quantities as are needed to maintain the requisite amount of gas in the reservoir or holder G.

What I claim as my invention, and desire to secure by Letters Patent, is—

- 10 1. The combination, in an air-carbureting apparatus, of an air-pump cylinder, the cylinder of an engine to be operated by hydrocarbon vapor arranged in line with said pump-cylinder, an interposed mixing-chamber constituting or communicating with a gas-reservoir, ducts for discharging both said cylinders into said mixing-chamber, pistons fitted to said cylinders, and a piston-rod connecting said pistons and working through said mixing-chamber, 15 substantially as and for the purpose specified.
- 20 2. The combination, in an air-carbureting apparatus, of an air-pump cylinder, a hydrocarbon-engine cylinder arranged in line therewith, an interposed mixing-chamber, to which said cylinders are secured at the ends and by which they are supported, a gas reservoir or holder provided with a movable top arranged above and supported upon said mixing-chamber, ducts for discharging and delivering hydrocarbon 25 vapor and air from said cylinders to said mixing-chamber, pistons fitted to said cylinders, and a single piston-rod, to which said pistons are connected, working through said mixing-chamber, substantially as and for the purpose specified.
- 30 35

3. The combination of the air-pump cylinder A and piston B, the engine-cylinder C and piston D, the rod E, connecting said pistons, the interposed mixing-chamber F, the valve H, the disk I, the curved arms J J, the rock-shaft K, 40 and mechanism actuated by said rock-shaft for operating the valve H, all arranged and operating substantially as specified.

4. The combination, in a carbureting apparatus, with an air pump, a hydrocarbon-engine, 45 means for heating the valve-chest of said engine externally, and a gas reservoir or holder comprising a movable top, of a pump for supplying hydrocarbon liquid to said valve-chest, mechanism actuated by a spring or weight for 50 operating the plunger of said pump, mechanism connected with the engine for moving said plunger in one direction and setting the spring or weight, a catch for holding said spring or weight when so set, and a rod connected with 55 the top of said reservoir or holder for releasing said spring or weight, substantially as and for the purpose specified.

5. The combination, with the air-pump and operating-engine, of the reservoir or holder G 60 and movable top G', pump O, lever P, spring R, or a weight, catch s, rod S, trip-lever M, and slotted link Q, all arranged and operating substantially as specified.

HERBERT COTTRELL.
